UNITED STATES PATENT OFFICE.

ADOLPHUS D. GOODWIN, OF SALEM, VIRGINIA.

DOOR-SPRING.

SPECIFICATION forming part of Letters Patent No. 432,398, dated July 15, 1890.

Application filed March 10, 1890. Serial No. 343,344. (No model.)

To all whom it may concern:

Be it known that I, ADOLPHUS D. GOODWIN, a citizen of the United States, and a resident of Salem, in the county of Roanoke and State of Virginia, have invented certain new and useful improvements in Door-Springs; and I do declare the following to be a full, clear, and exact description of the invention, such as will enable others skilled in the art to which it applies to make and use the same, reference being had to the accompanying drawings, and to letters of reference marked thereon, which form a part of this specification.

Figure 1 of the drawings is a perspective view showing the device applied to a door, and Fig. 2 is a plan view of the device.

This invention relates to certain improvements in door-springs; and it consists in the construction and novel combination of parts, as will appear from the following description and accompanying drawings.

In carrying out my invention I employ a lever A, which is pivoted near one end upon a horizontal bracket *a*, fastened to the door-frame directly above the door. This lever carries two frictional rollers or wheels *b*, preferably grooved, by means of axial studs *c*, riveted or headed into said lever, one at each side of its fulcrum and to a parallel bar *c'*.

The free end of the lever A plays in a keeper or eye *d*, secured in any suitable way to the door *B* near its outer upper corner edge. Directly above the keeper or eye *d* and fastened to the door-frame is a bracket *e*, which forms

the fulcrum of a lever *C*, to which is pivoted near its fulcrum a second lever *C'*, the counterpart of the lever *C*, and both having their free or diverging ends engaging or bearing upon the peripheries of the rollers or wheels *b*.

The levers *C C'* are held in forcible contact with the rollers or wheels *b* by a spring-clasp *f*, which engages opposite notches *g* in said levers, a series of which is provided in each lever. This arrangement permits of the adjustment of said clasp upon said levers, according to the amount of spring-pressure it is desired to impart to the levers to effect the closing of the door with a greater or less force.

It will be observed that as the door is opened, the keeper on the latter engaging the

lever A will carry the free end of said lever with it, causing the rollers or wheels on its inner end to force or spread apart the free ends of the levers *C C'*, thus putting the door-lever A under tension or pressure, which of course will have the effect to automatically close the door when released, as in passing in and out.

It will be observed that the maximum separation between the levers *C C'* takes place just as the door passes the plane of the rear edge of the door frame or opening. Consequently the lever in its reverse movement, as when the door is carried back against the wall, is relieved of pressure or tension. The spread-apart or free ends of the levers *C C'* then return, under the action or pressure of their spring-clasp, to their normal position, embracing or engaging the rollers or wheels as before, but reversed. Thus the door when set wide open and back against the wall cannot be accidentally closed or blown to. It will also be observed that the levers *C C'* are formed a short distance inward from their flaring or free ends with re-entrant angles *c* ^x *c'* ^x, the outer arm of which stands a short distance rearward from the inner one, whereby, even though the door be moved rearward past the plane of the rear edge of the door-frame, yet the door will remain or stand otherwise unassisted at this point or angle by reason of the engagement of said angles with the rollers or wheels *b*.

Having thus described my invention, what I claim, and desire to secure by Letters Patent, is—

1. The door-spring comprising the lever pivoted to a bracket secured to the door-frame and provided at each side of its fulcrum with studs carrying frictional rolls or wheels, said lever engaging a keeper or eye on the door, the additional levers, one pivoted to the door-frame and having re-entrant angles, one at the extreme outer end of one lever and facing outward and the other some distance inward from the outer end of the other lever and facing inward, said angles engaging said rolls, and the spring-clasp embracing said additional levers and engaging a series of notches in each lever, substantially as set forth. 10c

2. The door-spring comprising the spring-connected levers, one pivoted to the door-frame and provided with re-entrant angles, one at the extreme outer or free end of one lever and facing outward and the other some distance inward from the outer or free end of the other lever and facing inward, and the lever also pivoted to the door-frame and engaging a keeper on the door, said latter lever

carrying wheels or rolls arranged one upon each side of its fulcrum and engaging said angles, substantially as specified.

In testimony whereof I affix my signature in presence of two witnesses.

A. D. GOODWIN.
